FOOTWEAR

Augusto Rivelli, Baltimore, Md.

Application May 23, 1939, Serial No. 275,304

1 Claim. (Cl. 12—142)

This invention relates to footwear, and it is a particular object of the invention to provide an article of footwear wherein the inner sole and outer sole are in combination and so constructed 5 as to readily allow the securement thereto of the shank and upper.

It is also an object of the invention to provide an article of footwear wherein the construction is such to allow the forward portion of the combined inner and outer sole to readily flex thereby assuring an article of footwear that may be worn with a maximum of comfort.

The novel features of my invention will herein-after be definitely claimed.

15 In order that my invention may be the better understood, I will now proceed to describe the same with reference to the accompanying drawing, wherein:

Figure 1 is a longitudinal sectional view taken 20 through an article of footwear constructed in accordance with an embodiment of my invention, a portion of the upper being diagrammatically indicated by broken lines;

Figure 2 is a fragmentary detailed sectional 25 view taken substantially on the line 2—2 of Figure 1;

Figure 3 is a view in top plan of the combined inner and outer sole unapplied.

As disclosed in the accompanying drawing, A 30 denotes a shoe upper of desired style or design including the usual counter 1 and lining 2 and which upper A has its rear side marginal portions and heel portion underlying and suitably secured to the shank piece 3.

35 The combined inner and outer sole S, as herein comprised, is formed from a single piece of stock cut into desired design.

The inner sole 4 has its marginal edge inwardly spaced a desired distance with respect to the marginal edge of the outer sole 5 and the fore part of the inner sole 4 and the outer sole 5 are separated by a channel 6 providing a forward marginal flap 7. The heel and shank portion of the upper sole 4 is completely separated from such adjacent portion of the outer sole 5 whereby there is provided a heel and shank flap 8. It is to be particularly noted, however, that the fore part of the soles 4 and 5 with the exception of the marginal flap 7 are integrally connected at the fore-part.

After the shank and heel marginal portions of the upper A have been attached to the shank piece 3, the heel and shank flap 8 is inserted through the open bottom portion of the fore part 55 of the upper A and the combined inner and outer sole S is moved rearwardly so that the shank piece 3 will be properly received between the sole S

proper and the flap 8 and to properly fit the rear portion of the sole with the upper. After this placing of the sole S the lower or inturned marginal portion of the fore part of the upper A is engaged between the marginal flap 7 and the outer sole proper. This assembly can be readily accomplished and after which the lower or inturned margins of the upper A and the marginal portions of the sole S are connected as desired and preferably cemented although, if preferred, such parts can be sewed together or nailed together. After the upper A and the combined sole S have been assembled the shoe, of course, will be finished in the regular way.

It is to be particularly stated that before the 15 heel and shank flap 8 is secured into position upon the shank piece, preferably by adhesion, the heel H is applied and the securing nails are driven down through the heel portion of the shank piece and through the heel portion of the outer 20 sole 5 into the heel H. This is of particular advantage as it not only facilitates the desired mounting of the heel H but also permits the heel H to be applied in a manner to avoid the possibility of the pointed ends of the nails 9 passing up 25 through the applied flap 8 with resultant inconvenience to the wearer which would be liable to occur if the nails 9 were driven through the heel from the outer face. After the heel H is mounted the conventional top lift 10 is applied in the 30 usual way.

In an article of footwear as herein disclosed a shank stiffener 11 of any desired type can be readily placed below the heel and shank flap 8 and the shank piece 3 whereby such support will 35 be concealed.

I claim:

A method of making footwear which consists in taking a combined inner sole and outer sole having a channel in the side edge thereof at the fore part of the combined sole and having the heel and shank portion of the inner sole completely separated from the outer sole to provide a heel and shank flap which is integral with the fore part of the outer sole, placing the combined sole upon a shoe upper having attached to it a shank piece with the heel and shank flap extending over the shank piece and the inturned marginal portion of the fore part of the upper extending within the channel at the fore part of the combined sole, securing the forward inturned marginal portion of the upper and the combined sole one to the other, nailing from within the upper a shoe heel to the heel portion of the outer sole and shank piece and then securing the heel 55 and shank flap to the shank piece.

AUGUSTO RIVELLI.
